UNITED STATES PATENT OFFICE.

ALFRED SOMMERVILLE CALDWELL, OF INVERKEITHING, SCOTLAND.

APPARATUS FOR TREATING PULP.

No. 886,186.

Specification of Letters Patent.

Patented April 28, 1908.

Application filed November 29, 1907. Serial No. 404,361.

To all whom it may concern:

Be it known that I, ALFRED SOMMERVILLE CALDWELL, a subject of the King of Great Britain and Ireland, residing at Inverkeithing, in the county of Fife, Scotland, have invented Improvements in Apparatus for Treating Pulp, of which the following is a specification.

This invention has reference to that kind of apparatus for treating pulp wherein there are employed in conjunction with a suitable beating roll provided with appropriate knives or plates, other plates, supported in a yielding manner by fluid pressure in such a way as to exert a flattening and softening action upon fibers under treatment, the last mentioned plates being fixed in a plate box which is located in an outer box provided with an elastic diaphragm on which the bottom of the plate box rests, a chamber for liquid, such as water, being provided between the said elastic diaphragm and the bottom of the outer box to form a yielding support for the plate box.

It has been found in practice that such apparatus, as heretofore constructed, cannot be relied upon, its efficiency being liable to become impaired in consequence of entry and gradual accumulation between the inner and outer boxes of solid matters which interfere with and more or less prevent the necessary resilient action, and the present invention is designed to obviate this evil. For this purpose there is combined with the plate box and outer box, an elastic closure adapted to effectually close communication between the trough in which the beating roll works and the interior of the outer box, while at the same time leaving the plate box free to move sufficiently to admit of the necessary adjustment and resilient action relatively to the roll.

The closure may be a diaphragm of india rubber fitting accurately over the top edges of the plate box and outer box and so secured as to form a fluid tight joint therewith. In some cases this diaphragm may be corrugated. Provision is also made for the introduction of lubricant between the adjacent surfaces of the plate box and the outer box, and for indicating any leakage of liquid from the lubricant chamber formed by and between the boxes and the elastic diaphragm and elastic closure.

In order still further to insure the necessary free movement of the plate box within

the outer box, antifriction rollers or other antifrictional devices are or may be provided between them. In some cases, especially where the plate box is of considerable length, side wings or ribs are or may be provided, so arranged as to prevent endwise tilting or inclination of the plate box.

The outer box is or may be located in an appropriate den. There may be more than one den provided with plate boxes as described. In some cases, one or more dens in a machine may be provided with a plate box or boxes with outer boxes and devices according to the present invention and one or more other dens with sets of apparatus, such as fixed knives, appropriately constructed to perform cutting operations such as do not necessitate the resilient action desirable where mere flattening and softening of the fibers are to be effected.

Apparatus according to this invention can be variously constructed, and it is applicable to various classes of beating machines including disk machines and refiners.

In the accompanying illustrative drawings, Figure 1 shows in cross section, a combined plate box and outer box according to this invention, removed from a beating engine of the kind known as a Hollander. Figs. 2 and 3 are side elevations of portions of two known forms of such machines provided with the improved combined plate box and outer boxes. Fig. 4 is a detail view showing a modification. Fig. 5 is a side elevation, partly in section, and Fig. 6 a cross section on the line A A of Fig. 5, showing a refining machine provided with combined plate boxes and outer boxes according to the invention; Fig. 7 is a section of one of the combined plate boxes and outer boxes of Fig. 5, drawn to a larger scale, and Fig. 8 is a part longitudinal section thereof taken on the line B B of Fig. 7.

As shown in Figs. 1 and 2, a is a movable plate of the kind referred to having a concave surface b approximating to the peripheral surface of the beating roll c and carried by a plate box d through the intermediary of wooden or like packing strips e and f.

g is the ordinary outer box provided with a separate bottom plate h, the two parts being secured together by bolts and nuts i and clamping between them, at its edges, the elastic diaphragm j which is formed of good soft india rubber upon which the bottom of the plate box d rests and which forms

a yielding support for such box and also constitutes part of the liquid chamber *k* ordinarily employed to allow of automatic adjustment of the position of the plate *a* with respect to the heating roll *c* in a well known manner.

m is a diaphragm of elastic material, for example good soft india rubber, that covers the upper ends of the boxes *d* and *g* and through which the shank *a*¹ of the plate *a* extends. The said diaphragm is secured at its edges to the parallel free edges and ends of the boxes by metal bars *n* which are secured to the boxes, as by bolts and nuts *n*¹, so as to produce a fluid tight joint between the parts and permit of free movement of the plate box *d* within the outer box *g* without permitting matter to enter between the coacting surfaces of the boxes and affect such movement. The diaphragm *m* is preferably made with a curved or corrugated part *m*¹ to increase its flexibility.

o are antifriction balls provided for the same purpose of facilitating the movement 25 of the plate box *d*, each set of balls being conveniently housed in a recess *h* in the outer box *g*.

It will be understood that the outer box *g* is located in an appropriate den in the roll 30 trough *p*, the machines shown in Figs. 2 and 3 being provided each with three such dens *p*, each provided with a combined plate box and outer box as described.

In Fig. 2, *q* represent water inlet pipes 35 each leading to the corresponding port *k*¹ (Fig. 1) of the liquid chambers *k* of the corresponding outer box *g*. *q*¹ are gages for indicating the fluid pressure in such chambers; *q*² cocks for controlling the supply of liquid 40 to the chambers, and *q*³ outlet pipes, controlled by cocks *q*⁴, by which liquid can be drained from the said chambers when necessary.

To lubricate the interior of the outer box 45 *h*, or each outer box, one or each end of such box may be provided with one or more holes *h*² (see Figs. 1 and 2) through which lubricant, such for example as a mixture of soft soap and plumbago, can be introduced 50 by any convenient means such as a brush, mop or rod. Each outer box *g* may also be provided at one end with a hole *r* and attached pipe *r*¹ (Fig. 3) to indicate any leakage of liquid from the outer box *g*, such as 55 would take place should either of the diaphragms *j* or *m* become fractured during working and allow water to pass from the chamber *k* or trough *p* into the box *g*.

Fig. 4 shows a modification wherein the 60 balls *o* of Fig. 1 are replaced by strips *o*¹ of brass or other suitable metal attached to the sides of the plate box *d* and having rounded extremities to insure easy movement of such box.

65 Referring now to Figs. 5, 6 and 7 which

illustrate a refining machine, a number of outer boxes *g* are arranged equidistantly in a circle around the roll *c* and attached at their ends to and between disk plates *s* which are capable of being rotated upon rollers *s*¹, to facilitate the assembling of the parts, but which are normally held stationary by clamping the same, as by bolts *s*², to stationary brackets or feet *s*³. The spaces between the respective boxes *g* are occupied by blocks *t* of wood or other suitable material to constitute, in effect, dens for the boxes, the said blocks *t* being attached to the boxes by straps *t*¹ attached by studs *t*² to bosses on the boxes. Each outer box *g*, in this example, as shown 70 more particularly in Fig. 7, contains three independently movable plate boxes *d* placed one behind the other and made in the form of recessed bars having lateral webs *d*² which are faced so that they can slide smoothly one 75 upon another and against the inner surface of the box *g*. A sheet *m* of india rubber covers the open end of the outer box *g* to the edges of which it is secured by clamping strips *n* and screws *n*¹, as in Fig. 1, the said sheet being formed with slots, through which the shank portions *a*¹ of the plates *a* pass, and extending over the edges of the boxes *d* between which and the plates *a* it is clamped by bolts *u* which extend through the plates *a* 85 and boxes *d* into openings *x* in the webs thereof (Fig. 8) and are tightened up by nuts *v*.

What I claim is:

1. In an apparatus for treating pulp, the combination with a movable plate carrier 100 with plate and a stationary outer box having an elastic diaphragm upon which said plate carrier bears and, between its lower end and said diaphragm, a chamber for liquid under pressure to form a yielding support for said movable plate carrier, of means adapted to prevent entry of pulp material between said movable plate carrier and outer box while leaving said carrier free to move sufficiently to admit of the necessary adjustment and resilient action relatively to the beating device with which said movable plate holder with plate is used.

2. In apparatus for treating pulp, the combination with a movable plate carrier with 115 plate, and a stationary outer box provided at its lower end with a yielding support for said carrier, of an elastic diaphragm secured to said carrier and outer box and adapted to prevent pulp material passing between the 120 adjacent surfaces of said carrier and box.

3. In apparatus for treating pulp, the combination with a movable plate carrier with 125 plate and a stationary outer box having an elastic diaphragm upon which said plate carrier bears and a chamber between its lower end and said diaphragm for liquid under pressure to form a yielding support for said movable plate carrier, of a diaphragm of elastic material secured to the movable plate carrier 130

and stationary outer box to prevent entry of pulp material between the adjacent surfaces of these parts.

4. In apparatus for treating pulp, the combination with a movable plate carrier with plate, and a stationary outer box provided at its lower end with a yielding support for said carrier, of an elastic diaphragm secured to said carrier and outer box and adapted to prevent pulp material passing between the adjacent surfaces of said carrier and box.

5. In apparatus for treating pulp, the combination with a movable plate carrier with plate and a stationary outer box provided with a yielding liquid container having an elastic side adapted to form a yielding support for said carrier, of an elastic closure adapted to prevent entry of pulp material between the adjacent surfaces of said carrier and box, said box being provided at a point between said liquid container and elastic closure with a leakage outlet through which liquid entering the box through failure of the liquid container or elastic closure can escape.

6. In apparatus for treating pulp, the combination with a pulp holder, a beating device therein, a co-acting plate, a movable carrier for said plate, and a stationary outer box provided with an elastic diaphragm upon which said plate carrier rests and a chamber for liquid between said diaphragm and the bottom of said box, of means for preventing entry of material from said pulp holder to the adjacent sliding surfaces of said carrier and box while leaving said carrier free to move toward and from said beating device.

7. In apparatus for treating pulp, the combination with a pulp holder, a beating device therein, a co-acting plate, a carrier therefor adapted to slide towards and from said roll, and an outer box provided with an elastic support subject to fluid pressure for supporting said plate carrier, of an elastic diaphragm secured to the ends of the carrier and box adjacent to the pulp holder for preventing entry of material from said pulp holder to the sliding surfaces of said plate carrier and box.

8. In apparatus for treating pulp, the combination with a pulp holder, a beating roll therein, a co-acting plate, a sliding carrier therefor, and a stationary holder for the sliding support, said holder comprising two parts having an elastic diaphragm secured between them and upon which the plate carrier rests, and a chamber for liquid between said elastic diaphragm and the bottom part of said holder, of an elastic closure arranged between such sliding plate carrier and stationary holder and adapted to prevent material passing from said pulp holder to the adjacent surfaces of said parts.

9. In apparatus for treating pulp, the combination with a pulp holder, a beating device therein, a co-acting plate, a sliding carrier therefor, and a stationary outer box with yielding support for said plate carrier, of means for preventing entry of material from said pulp holder to the space between said carrier and box, and antifrictional devices between said carrier and box.

10. In apparatus for treating pulp, the combination with a pulp holder, a beating roll therein, a co-acting plate, a sliding carrier therefor, and a stationary outer box with yielding support for said sliding carrier, of an elastic closure arranged between said carrier and outer box and adapted to prevent material passing from said pulp holder to the adjacent surfaces of said carrier and box, and antifrictional devices engaging such sliding carrier and box.

11. In apparatus for treating pulp, the combination with a pulp holder, a beating device therein, a co-acting plate, a sliding carrier therefor, and a stationary outer box with yielding support for said plate carrier, of an elastic closure for preventing entry of material from said pulp holder to the sliding surfaces of said carrier and outer box, said box having one or more openings therein for the introduction of lubricant between said surfaces.

12. Apparatus for treating pulp, comprising a pulp holder, a beating roll therein, a plate co-acting with said roll, a plate box in which the plate is rigidly mounted, a containing box in which the plate box is free to slide towards and from the beating roll, said containing box having an elastic diaphragm upon which said plate box bears and a chamber between its lower end and said diaphragm for liquid under pressure to form a yielding support for said plate box, and an elastic diaphragm connecting the edges of both boxes which are adjacent to the beating roll.

13. Apparatus for treating pulp, comprising a pulp holder, a beating roll therein, a plate co-acting with said roll, a plate box in which the plate is rigidly mounted, a containing box in which the plate box is free to slide towards and from the beating roll, said containing box having an elastic diaphragm upon which said plate box bears and a chamber between its lower end and said diaphragm for liquid under pressure to form a yielding support for said plate box, an elastic diaphragm connecting the edges of both boxes which are adjacent to the beating roll, and means for introducing lubricant between the said boxes.

14. Apparatus for treating pulp, comprising a pulp holder, a beating roll therein, a plate co-acting with said roll, a plate box in which the plate is rigidly mounted, a containing box in which the plate box is free to slide towards and from the beating roll, said

containing box having an elastic diaphragm upon which said plate box bears and a chamber between its lower end and said diaphragm for liquid under pressure to form a yielding support for said plate box, an elastic diaphragm connecting the edges of both boxes which are adjacent to the beating roll, and means for indicating leakage of liquid from

the portion of the outer box between said diaphragms.

Signed at Edinburgh this thirteenth day of November 1907.

ALFRED SOMMERSVILLE CALDWELL.
